FLUID OPERATED TOOL

John R. Hoffman, Madison, Wis., assignor to
Madison-Kipp Corporation, Madison, Wis., a
Corporation of Wisconsin

Application April 29, 1931. Serial No. 533,809

3 Claims. (Cl. 121—20)

This invention relates to fluid-operated tools, and especially to those of the reciprocating type, such as files, saws and the like.

The primary purpose of the invention is to furnish a small, practical tool of the character mentioned adapted for shop or general use. The body of the tool is designed to permit the tool to be held in a natural position in the hand, thereby facilitating operation of the tool in any position and adapting it for easy access to all types of work. Manufacture of the parts of the lightest metal possible consistent with efficiency, also aids materially in the facility with which the tool may be operated. Further provision is made for enabling the tool element to be guided readily over irregular surfaces.

A particularly important feature of the device consists of the improved means for controlling distribution of the motive fluid which actuates the piston connected to the reciprocating tool body. By these means, direct and complete control of the fluid is maintained during its passage through the tool. In addition, the fluid-distributing means are designed to cause a special retarding effect on the movements of the piston which is highly desirable in certain tools of this type.

Particular provision is made for the elimination of all vibration in the operation of the tool, thereby effecting smooth cutting strokes of the tool element.

A further feature is the efficient utilization of the exhaust fluid to operate the means for distributing the motive fluid to the power cylinder. Use is also made of the exhaust fluid to aid in slowing up the reciprocating movement of the piston.

Other objects will appear hereinafter.

Reference is had to the accompanying drawings showing a practical embodiment of my invention, and in which:

Fig. 1 is a side elevation of the tool;

Fig. 2, a rear elevation thereof, partly broken away to show the rotor for operating the fluid-distributing valve;

Fig. 3, a section taken on line 3—3 of Fig. 4, showing the fluid supply valve closed and the piston in mid-position completely closing the cylinder exhaust port;

Fig. 4, a section taken on line 4—4 of Fig. 3, with the parts in the same position, showing the fluid-distributing shaft or valve;

Fig. 5, a section taken on line 5—5 of Fig. 3;

Fig. 6, a section taken on line 6—6 of Fig. 1;

Fig. 7, a section taken on line 7—7 of Fig. 4;

Fig. 8, a perspective of the fluid-distributing valve and operating rotor;

Fig. 9, a side elevation of the same;

Fig. 10, a section on line 10—10 of Fig. 9, showing the segmental fluid-distributing groove for the motive fluid;

Fig. 11, a side elevation of the bushing or bearing for the distributor valve;

Fig. 12, a section taken on line 12—12 of Fig. 11;

Fig. 13, a fragmentary section similar to Fig. 3, showing a succeeding position of the parts as 65 the fluid supply valve is opened to feed motive fluid to the right end of the cylinder and force the piston slightly to the left;

Fig. 14, a similar view as the piston continues its movement to the left to open the exhaust port, 70 and the distributing valve begins to feed fluid to the left end of the cylinder;

Fig. 15, a similar view showing the piston forced to the right end of the cylinder, again opening the exhaust port as continued rotation 75 of the valve causes fluid to be fed only to the left end of the cylinder.

In the drawings, the body 1 of the tool, which preferably is a die-casting of zinc or other suitable light metal, is formed with a handle 2 and a barrel 3. The tool body, as shown most clearly in Fig. 1, is designed so as to simulate closely a standard-type pistol or revolver. The "pistol grip" thus provided greatly increases the ease and accuracy with which the tool may be handled under all conditions.

The tool-element actuating piston 4 is located for reciprocation in a cylinder 5 formed in the upper part of the tool body. A piston rod 6 extends from piston 4 through the barrel of the tool and at its forward end is provided with a chuck 7 adapted to receive any desired type tool steel or element, shown in this instance as a file 8.

An extended bearing for piston rod 6 is afforded by the reduced passage 9 at the inner end of barrel 3. A bushing 10 threaded into the end of the main barrel chamber 11 provides a suitable bearing for the outer end of piston rod 6. 100 Piston rod 6 and bushing 10 are keyed together suitably at 12 so as to prevent rotation of the piston rod without interfering with the reciprocating movement thereof necessary to operate the file 8.

Screw plugs 13, 14 at the rear end of cylinder 5 provide for ready removal or insertion of piston 4 and piston rod 6, when desired. Detachment of file 8 and collet nut 7' of the chuck from the forward end of piston rod 6 is necessary, of 110

course, before the piston rod and piston 4 can be removed.

The means for controlling supply of motive fluid to the tool and distributing it in order to effect the desired reciprocation of piston 4, piston rod 6 and the attached file as a unit will be described now.

Piston cylinder 5 is provided with forward and rear fluid inlet ports 15, 16, respectively, and a single exhaust port 17 controlled by piston 4. Motive fluid, preferably compressed air, is supplied to the lower end of a passage 18 in the handle of the tool by a flexible tube 19 leading from a suitable source of supply. From passage 18 the motive fluid is adapted to be conducted alternately to opposite sides of piston 4 through inlet ports 15, 16, as described below.

Supply passage 18 opens at its upper end into a valve chamber 20. The rear end of chamber 20 is closed by a screw plug 21, while the forward end of the valve chamber opens into a smaller chamber 22. A throttle valve 23 controls communication between chambers 20 and 22, a spring 24 serving normally to hold valve 23 closed and thereby prevent passage of motive fluid beyond this point. Stem 25 of valve 23 projects forwardly through an opening in the tool handle for engagement by a valve-actuating trigger 26 pivoted on a pin 27 carried by the barrel of the tool.

When control valve 23 is operated by trigger 26, as shown in Fig. 13, compressed air enters passage 22, and thence flows into an inclined passage 28 (Fig. 4). The upper end of passage 28 leads to an opening 29 in a bushing or bearing member 30 fixedly located in a suitable transverse opening provided in the body of the tool. This bushing 30 is shown in detail in Figs. 11 and 12.

Mounted for rotation in bushing 30 is a distributing valve or shaft 31, the left end of which is reduced, as shown in Fig. 4, to receive an actuating rotor 32. Preferably, rotor 32 is cast on distributor valve 31 so that the two parts function as a unit, and there is no chance of their becoming detached or loose.

Towards its right end, valve shaft 31, as shown in Fig. 4, is formed with an annular groove 33 into which the motive fluid enters from opening 29 in bushing 30. From annular groove 33 the motive fluid is conducted through a longitudinal groove 34, and thence into a transverse segmental groove 35, all of these grooves being formed in the body of the distributor valve.

Segmental groove 35 is located in alignment with two openings 36, 37 provided in bushing 30. These openings connect with a pair of passages 38, 39 formed in the body of the tool and connected at their upper ends with the inlet ports 15, 16 of piston cylinder 5. This appears most clearly in Figs. 13, 14 and 15, wherein the distributor valve 31 is shown in the various positions which it assumes in feeding the motive fluid to opposite ends of cylinder 5.

With the arrangement described, it will be seen that motive fluid entering segmental groove 35 will be distributed thereby alternately to inlet ports 15, 16, effecting the desired reciprocation of piston 4, when properly assisted by the fluid exhausting mechanism described shortly.

It will be noted that the angular extent of segmental groove 35 is such that, as shown most clearly in Fig. 14, the groove serves to start feeding motive fluid to one of the cylinder inlet ports 15, 16 just as it begins to discontinue the feed

of motive fluid to the other inlet port. The purpose of this will appear hereinafter.

Piston cylinder 5 is provided with a single centrally located exhaust port 17 (see Fig. 3), which is adapted to be entirely closed by piston 4 when the latter is in its mid-position. However, when piston 4 is moved toward either end of its cylinder, the motive fluid which has effected this movement of the piston escapes from exhaust port 17 and enters a segmental groove 41 formed on the outside of the distributor valve bushing 30. The angular extent of groove 41 is such that at its lower ends, as shown in Fig. 3, it communicates with horizontal passages 42, 43 formed in the body of the tool.

Extending from the ends of these passages 42, 43 are angularly disposed reduced passages 44, 45 opening into the rotor chamber 46 for the purpose of ejecting the exhaust motive fluid against the buckets 47 of the rotor 32 to operate the latter. This, as stated hereinbefore, serves to impart the necessary rotary movement to the distributor valve 31 in order to feed the motive fluid to the piston cylinder. For sake of clearness, the course which the exhaust fluid takes is indicated by arrows in Fig. 1, although in this figure piston 4, is not, in fact, in fluid-exhausting position.

The detailed construction of rotor 32 appears most clearly in Figs. 8, 9 and 10. Here, it will be noted, an annular flange 48 is formed on the inner face of the rotor in order to prevent the exhaust fluid from escaping at the inner ends of the rotor buckets or vanes 47. As shown in Fig. 4, rotor 32 and its parts are so constructed and arranged with reference to the associated parts of the tool body as to provide for highly efficient operation in performing its function as the actuating means for the motive fluid distributing valve.

The outer side of rotor chamber 46 is closed by a cap 49 threaded in place, and provided on its inner face with a central depression containing a single ball bearing 50. When cap 49 is screwed into place, ball 50 forms an effective thrust bearing for rotor 32 and its fluid-distributing shaft 31. The exhaust motive fluid escaping from the periphery of rotor 32 passes out of rotor chamber 46 through an outlet opening 51 (see Fig. 1). Spanner wrench sockets 52, 53 in the outer face of the rotor chamber covering 49 provided for ready removal and replacement of this member.

The purpose of arranging segmental groove 35 in distributor valve 31 so that communication between it and one of the inlet ports 15, 16 is not cut off before communication with the other port is opened, is to slow down the reciprocatory movement of piston 4 and the attached tool part. This is highly desirable in certain tools, particularly those of the file type. This arrangement of the distributing means also prevents excessive hammering of the piston and reduces vibration in the tool. Also, since segmental groove 35, due to its angular extent, is always in communication with either inlet 15 or 16, no matter what the position in which distributor valve stops, starting of the tool is assured when the throttle valve 23 is opened.

Reference is now had to Figs. 13, 14 and 15 which disclose the various positions of the tool parts in operation. In Fig. 13, the motive fluid is shown as entering the cylinder inlet port 16, being fed thereto by the segmental groove 35 in

distributor valve 31. It will be noted that at this time groove 35 is only in communication with inlet port 16, thereby forcing piston 4 to the left. At this time, exhaust valve 17 is about to open and permit the motive fluid at the right of piston 4 to escape.

As rotation of distributor valve 31 continues, this movement being in a counterclockwise direction, piston 4 moves further to the left, but just before it reaches its extreme position, segmental groove 35, as shown in Fig. 14, communicates partially with the opposite inlet port 15. It will be noted that this occurs before communication between segmental groove 35 and inlet port 16 has been cut off. As a consequence, a small quantity of motive fluid is fed into the space between piston 4 and the end of its cylinder before the piston has reached the end of its movement. This provides an effective cushioning of the piston movement, and not only cuts down excessive hammering, but provides for the very desirable slowing down of the movement of the piston.

When the parts have reached this position, exhaust port 17 is in full open condition, permitting the exhaust fluid to escape and pass to rotor chamber 46 to operate the rotor and the attached distributing valve, as described hereinbefore.

Leaving the parts as shown in Fig. 14, distributor valve 31 continues its rotary movement, thereby cutting off communication with inlet port 16 and moving into full communication with inlet port 15. This forces piston 4 back to the right, but prior to the piston reaching its right hand position, the inlet port at this end of the cylinder, in this case port 16, is opened before fluid stops feeding to port 15. As a result the movement of the piston is cushioned and slowed down, as was the case when it moved in the opposite direction. About this time, exhaust port 17 is fully opened and the exhaust motive fluid escapes to effect continued rotation of distributor valve 31. From this point, the movements of the parts are continued as described above, the piston 4 and the attached tool part being moved steadily back and forth as a result of the automatic functioning of the fluid distributing means.

In order to aid further in slowing down the reciprocatory movements of piston 4, provision is made for by-passing a portion of the exhaust motive fluid, so that it does not function to operate the distributor valve. In some cases, it is found that utilization of all of the exhaust fluid for this purpose causes the distributor valve to operate too fast, thereby effecting excessively rapid reciprocation of the file 8. As shown in the present embodiment of the invention, a by-pass or port 54 (see Figs. 1 and 4) is provided in piston cylinder 5 in transverse alignment with exhaust port 17. With this arrangement, both the exhaust port and by-pass 54 are adapted to be controlled by piston 4 in its movements back and forth in the cylinder. By-pass 54 opens into rotor chamber 46 (see Fig. 4) and such of the exhaust fluid as escapes therefrom, when the port is uncovered by piston 4, escapes with the rest of the exhaust fluid through outlet 51 in the rotor chamber.

As shown in Fig. 4, by-pass 54 is arranged at right angles to rotor 32 and in such position that exhaust fluid ejected therefrom impinges against the vanes or buckets 47 of the rotor. In this manner, the exhaust fluid escaping from port 54 serves to impart a drag or braking effect on the

movement of the rotor. This reduces the speed of rotation of distributor valve 31 and slows down the movements of piston 4, as will be understood readily.

Suitable lubricating means are provided in the handle of the tool. These means are intended to supply lubricant to the motive fluid so that when the fluid passes through the tool, the various parts will be properly lubricated. For this purpose, there is located in fluid supply passage 18 a spool 55, provided with outwardly flaring flanges at its opposite ends to frictionally support the spool in place. Surrounding the body of spool 55 is a layer of absorbent material 56 which may be saturated with lubricant supplied thereto by removing screw plug 57 (Fig. 4) located in the handle of the tool. Openings 58, 59 at opposite ends of spool 55 permit the incoming motive fluid to pick up the lubricant from the absorbent material 56 and carry it to the working parts.

A small wire screen 60 at the lower end of spool 55 prevents the possible entrance of foreign materials into the tool.

No claim is made herein to the general form of the tool body, nor to the throttle or fluid-supply control valve, since these features form part of the subject matter and are claimed in my prior applications, Serial No. 512,446, filed January 30, 1931, and Serial No. 512,700, filed January 31, 1931 (Patent No. 1,899,150). Also certain features of the fluid-distributing means and the lubricating means described herein are covered by said earlier applications.

The provision of bushing 10 at the outer end of barrel 3 affords means for readily guiding the tool over uneven surfaces, when a file element or the like is being used. In this case, the operator grasps the outer end of bushing 10, which is faceted for this purpose, as shown at 10' in Fig. 1, between the thumb and index finger of one hand and grasps the handle 2 with his other hand. The threaded connection between the bushing and the barrel of the tool permits the operator to rotate the bushing while the tool proper is held steady. In this manner, the file element 8 may be twisted and turned by means of bushing 10, because of the keyed connection 12 between these parts. Ordinarily, however, bushing 10 is screwed tightly in place and the file 8 is guided mainly by the hand in which the tool handle is grasped.

While a practical tool has been illustrated and described herein, it is obvious to those skilled in the art that various changes in the construction may be made within the scope of the invention, except as the same may be limited by the appended claims.

What is claimed is:—

1. In a fluid-operated tool, the combination of a tool body having a chamber provided with inlet ports; valve means for feeding motive fluid to said inlet ports; means for operating the valve means by the exhaust fluid from said chamber; and a piston in the chamber controlling a pair of different-sized, transversely aligned exhaust ports, the larger of which supplies actuating fluid to the valve operating means, while the other directs a jet of fluid against the valve operating means so as to retard movement thereof.

2. The combination in a fluid-actuated tool of a body having a piston chamber with inlet ports opening therein; a piston located in said chamber and adapted to control an exhaust port and a relief port; a rotary valve for distributing mo-

tive fluid to said inlet ports; a rotor for operating said valve; and means for operating the rotor by exhaust fluid from the piston cylinder, the rotor being so arranged that exhaust fluid escaping from the relief port exerts a retarding action thereon.

3. The combination in a fluid-actuated tool of a tool body having a chamber and inlet ports therefor; a piston in said chamber, said chamber 10 having an exhaust port controlled by the piston;

a rotary valve controlling distribution of motive fluid to the inlet ports; a rotor for operating the valve; a bushing in which said valve rotates, the exterior of the bushing being formed with a segmental groove connecting said exhaust port with 80 passages leading to the rotor for actuation thereof by the exhaust fluid; and valve means for controlling supply of motive fluid to the distributing valve.
